G. HAUFLER

PEPPER CASTER

Filed April 10, 1924

Fig. 1.

Fig. 2.

Inventor: *G. Hafler*

UNITED STATES PATENT OFFICE.

GOTTLOB HAUFLER, OF STUTTGART, GERMANY.

PEPPER CASTER.

Application filed April 10, 1924. Serial No. 705,704.

To all whom it may concern:

Be it known that I, GOTTLÖB HAUFLER, a citizen of the German Republic, and resident of Stuttgart, Germany, have invented a new and useful Pepper Caster, of which the following is a specification.

This invention relates to an improvement in pepper-casters of the kind in which the peppercorns are contained in a receptacle having a comparatively large bottom aperture and a grooved ball in this aperture, the ball being fixed to a spindle and this latter being provided with a handle, by means of which the ball can be rotated, its grooves then disintegrating the corns. My improvements in pepper casters of this kind consist, firstly, in providing the disintegrating ball with worm-like or spherical grooves instead of with parallel or co-axial ones, and secondly, in providing its spindle with two handles or equivalent members at one end of the spindle, the other at the other end thereof.

The thus improved pepper caster is illustrated, by way of example in the accompanying drawing, in which Figure 1 is a longitudinal or vertical section thereof, and Figure 2 is a horizontal or cross-section on line A—B of Figure 1.

The receptacle *a* consists, in the example shown, of wood, and is closed by a screw-lid *b*. The bottom of the chamber contain-

ing the peppercorns consists of a ball *k* which is secured to a spindle *d* having at either end a handle *h*. The ball *k* is provided with a continuous groove *c* running around it like a spiral, the convolutions being arranged preferably obliquely with respect to said spindle. The corns are disintegrated by turning the ball *k* by means of either of the handles *h* in one or the other direction.

I claim:

A pepper-caster, comprising, in combination: a receptacle adapted to receive the peppercorns and having a comparatively wide outlet passage, the wall of which is spherically contracted near the pepper corn-receiving receptacle-chamber; and forms an inwardly projecting edge at its upper end; means for closing the receptacle at its top; a comparatively large ball forming the bottom of the peppercorn receiving receptacle-chamber and being arranged in said wide outlet-passage and provided with a spirally-running groove adapted to co-operate with said edge; a spindle supported in the lower part of the receptacle-chamber, being firmly connected with said grooved ball, and a handle at either end of said spindle.

GOTTLÖB HAUFLER.
